FIG. 2.

UNITED STATES PATENT OFFICE

2,333,127

CUTTING KNIFE SUPPORT

Albert F. Shields, Jamaica, N. Y., assignor to
S. & S. Corrugated Paper Machinery Co., Inc.,
Brooklyn, N. Y., a corporation of New York

Original application February 10, 1940, Serial No.
318,293. Divided and this application May 3,
1941, Serial No. 391,703

2 Claims. (CL 164—66)

This invention is a division of my application, Serial No. 318,293, filed February 10, 1940, and relates to cutting knife mechanisms and more particularly to supports therefor, including supports for mechanism operable therewith.

In the manufacture of corrugated sheet material, it is frequently necessary to cut such sheet material into predetermined sections of standard length. This is most frequently done as the corrugated web comes from the machines which manufacture the same, the web led from these machines being cut to the proper width.

It is customary therefore to place the cutting machine at the terminus of the corrugated web manufacturing line so that the end product of the entire manufacturing process is a series of corrugated sheets of predetermined standard length. The cutting machines for this purpose are complicated and heavy while nevertheless requiring delicacy of adjustment. Thus, for instance, the same machine with the same cutting knives may, by simple adjustments, such as that shown in applications Nos. 320,471, filed February 24, 1940, and 318,294 filed February 10, 1940, and Patents Nos. 2,208,350 and 2,202,872, all of which are assigned to the assignee of this application, be arranged to cut sheets of varying lengths without interfering with or slowing down or changing the speed of movement of the corrugated web as it comes from the prior manufacturing processes.

That is, a machine which is cutting sheets 120" in length may by a simple adjustment be changed to cut sheets of 90", 60", 30" or any other dimension. In all cases, the cutting knives are driven primarily through a Reeves drive mechanism which varies the average speed of rotation of the cutting knife with respect to the corrugated web so as to produce a cutting operation at a selected interval for the purpose of producing a sheet of the selected length. And, in addition and working with the Reeves drive or adjustable the same time as the Reeves drive, either automatically or manually, other apparatus adds a cyclic variation in the speed of rotation of the cutting knives so that whatever the average speed of rotation thereof, the cutting knives will be traveling at the speed of the web during the actual cutting.

Since the Reeves drive itself and the various adjustments and the drums or shafts carrying the cutting knives are continuously rotating and frequently being varied in their adjustments and since the cutting knives themselves and all of the rest of the machinery including the Reeves drive

is periodically subjected to increased strain when the knives pass through the corrugated web, the machine itself must be sturdily and rigidly constructed and all parts thereof should as far as possible be interbraced and rigidified.

Heretofore, in cutting machines of this type, the elements thereof have to a great extent been separated or dispersed. Thus the Reeves drive which transmits power to the rotating cutting knives, and which is subjected to the greatest stresses, being driven at one end from the power source and at the other being subjected to the vibration and the periodic load of the passing of the knife through the sheet, has always been not so much a part of the machine integrated and unitary therewith, but rather an attachment thereto, to be placed in any desired position with respect thereto as space requirement provided. Also the input driving mechanism such as gears or chains and other apparatus have hitherto been separately housed or detached from the main body of the machine in some way.

The vibration entailed in the operation of the machine and the heavy periodic loads have frequently caused minor disarrangements of the Reeves drive and interrelated mechanism which, while not serious in themselves, nevertheless hasten the wear of the entire machine and also caused continued inconvenience in that frequent readjustments were necessary.

A principal object of this invention therefore is to integrate the entire assembly necessary for the cutting of the continuously traveling corrugated web. That is, to combine in a single unitary apparatus, which is interbraced, all of the elements necessary for the operation.

A further object of this invention is to arrange the Reeves drive so that it may be mounted within the apparatus itself and so that it may be protected by its mounting therein and be so arranged that vibratory forces and periodic changes in the load can have no effect on the adjustment or arrangement thereof.

Further objects of this invention are to cross brace and interbrace the entire apparatus along its outer surface in such a way that it presents the appearance of a single unitary structure, the parts thereof being accessible for adjustment and repair but the entire apparatus having nevertheless a completed and finished appearance and being protected.

Further objects and uses of this invention will in part be apparent and in part pointed out in the following description and drawings, in which:

Figure 1 is a view in perspective of a simplex

cutting machine made in accordance with my invention.

Figure 2 is a cross-sectional view taken on line 2-2 of Figure 1.

Figure 3 is a cross-sectional view taken on line 3-3 of Figure 2.

Referring now to Figures 1, 2 and 3, I have here shown a simplex cutting machine comprising cutting knives 10 and 11 respectively mounted on shafts 12 and 13 to interengage with each other once during each revolution of shaft 12 and 13 in order to sever the corrugated sheet material passing therethrough.

Referring specifically to Figure 2, the web of sheet material when it is received from the prior manufacturing processes may be fed by the conveyor belt 18 into and between the shafts 12 and 13 on to the platform or bed 19. The forward edge of the web, as it is thrust forward, passes between the feed rollers 20 and 21 which continue to carry it forward onto the bed 22. The cutting knives 10 and 11 are arranged to cut the web material at any selected interval after the forward edge thereof has passed between the feed rollers 20 and 21.

The sheet after it has been cut by the knives 10 and 11 nevertheless remains under the influence of feed rollers 20 and 21 and is forced forward on the bed 22 where it may be manually removed or the bed 22 may be so short that the forward rollers 20 and 21 may feed the cut sheet so that its center of gravity extends beyond the edge of the bed 22 so that it may fall off when it has left the feed rollers thus leaving the bed free for the next sheet.

As is seen in Figures 1 and 3, power is transmitted from the power shaft 29 through the bevel gears 30 and 31 to the shaft 32 which operates one of the members 36 of the Reeves drive 37. This Reeves drive 37 through the shaft 38 and appropriate gearing and connecting mechanism contained in the housing 43 operates one of the cutting knife assemblies, for instance, knives 10 and 11.

Other mechanism such as that shown in patents and applications above mentioned for varying the adjustments of the cutting knives, for varying the adjustments of the Reeves drive, and for integrating the adjustments of the Reeves drive and the cyclical adjustments of the cutting knives may also be placed in housing 39.

Such members may comprise a shaft driven from shaft 38 and housed in housing 43, the said shaft being parallel to but rotatable about shaft 38, a crank on the shaft, a crank on one of the knife drums and a link interconnecting the cranks, all as shown in Patent No. 2,202,872, issued June 4, 1940. Housing 39 may contain the gears interconnecting the driven knife drum shaft with the other knife drum shaft so that the two drums are driven together also as shown in Patent No. 2,202,872. The driving mechanism from the "Reeves" drive to the knife drums is housed in housing 43. Shaft 32 is extended to housing 39 to provide additional support for the shaft and also to make possible a power connection from an outside power source to shaft 32 at the end thereof in housing 39—the power connection being similar to that shown in dotted lines in housing 43, Figure 3. This last arrangement is provided to make the machine adaptable in its alignment with other apparatus in which the exact optimum location of the power source with respect to the machine cannot always be foreseen.

These members are not shown since they are not necessary to the present disclosure, it being sufficient to point out that the Reeves drive is connected to and is part of the power chain operating the cutting knives. Instead of mounting the Reeves drive as an attachment to the machine or outside the machine or in any intermediate relation to the present machine, the Reeves drive of the present invention has been made an integral part of the machine itself enclosed within the covering of the machine and supported on bracing structures which themselves form part of the machine.

Thus the housings 39 and 43 which house the associated mechanism are themselves supported on base 46, being riveted, welded or otherwise securely affixed thereto in any suitable manner.

Also the main driving gears 30 and 31, together with their respective shafts and supporting bearings are seen to be housed completely within the main housing where they run in the same oil bath with the housing gears.

The base 46 comprises a platform 47 (Figure 2) carrying supporting flanges 48 and 49 cast or integral therewith.

Brace 50 comprises main portion 51 and base portion 52 and is securely attached to the platform 47 by bolts or rivets 53 passing through said base flange 52. The brace 51 also comprises integral lateral flanges 55 and 59 (Figure 3) which are by means of bolts 56 and 61 securely attached to the housings 39 and 43.

Top brace 100 is a flanged member which may by bolts 101 passing through flanges 110 and 111 be connected between the housings along the top of the apparatus.

The brace 50 therefore securely integrates the housings 43 and 39 spacing them rigidly and even assisting in binding them to their base.

A similar brace 57 (Figures 1, 2 and 3) constitutes the entire opposite side of the machine and comprises a principal member 58 also having lateral flanges 55 which are bolted securely by bolts 56 to the end pillars 39 and 43. This brace 57 also has bottom flange 63 which is bolted securely by bolts or rivets 64 to the base 47.

In this manner by means of braces 50 and 57, the housings 39 and 43 are combined into a single unitary entity efficiently cross-braced to prevent any shifting or vibration of any part of the mechanism relative to any other part. Each brace 50 and 57 may, if desired, have openings therein covered by removable members to provide for ready access to the interior of the member for adjustment, cleaning, repair or other purposes.

Each brace 50 and 57 has L-shaped protrusions 61, 67 therefrom preferably integral with the associated brace and extending into the interior of the machine (see Figures 2 and 3).

Cross-bracing member 69 is mounted between the pair of L-shaped members 61, being secured thereto by means of bolts 71 passing through the respective associated flanges of the member 69 and the member 67. This serves further to rigidly interbrace and cross-brace the entire mechanism.

The Reeves drive 37 is mounted within this rigidly cross-braced and interbraced frame. As will be seen, the shafts 38 and 32 of Reeves drive 37 are effectively supported between the cross-brace 69 and the housing 43.

In this manner, the Reeves drive is made an integral part of the mechanism, is rigidly mounted within an interbracing, rigidifying framework

of the mechanism, is no longer an appendage to the mechanism but an essential and integral part thereof.

The Reeves drive cannot shift with respect to the mechanism by reason of its rigid and braced support, is no longer subjected to the various disadjustments which arise from uninhibited vibration, and is rigidly held in such manner that it cannot shift or become disadjusted by reason of the variations in loads imposed thereon.

The essential element, therefore, of this invention is the cross-bracing and interbracing of the entire machine, the mounting of the Reeves drive, power and input drive mechanisms not as appendages to the machine but as integral parts of the machine, the cross-bracing and support of the Reeves drive in the machine and the improvement in the appearance of the machine by means of the cross-bracing forming the outer walls of the machine and interbracing which presents a mechanism having a solid complete unitary appearance and on in which the various portions and mechanisms thereof are fully protected.

While I have shown in the foregoing description, a simplex cutting machine comprising one pair of cutting knives and suitable apparatus therefor, it will be obvious that the present invention may readily be utilized in a duplex cutting machine in the manner shown in my application Serial No. 318,293, filed February 10, 1940. Other means of bracing and arranging the various portions of the apparatus in the manner herein described will now be clear to those skilled in the art and I therefore prefer to be limited not by the disclosure herein, but only by the appended claims.

I claim:

1. An apparatus for cutting successive sheets from a continuous web, said apparatus comprising a pair of rotating cutting knives and means for adjusting the speed of rotation thereof, said cutting knives being mounted between end hous-

ings of said apparatus and said adjusting means including a Reeves drive, a power connection from a power source to said Reeves drive and a power connection from the Reeves drive to said cutting knives, a front brace between said end housings, said brace substantially enclosing the front of the apparatus, a rear brace between said end housings, said rear brace substantially enclosing the rear of the apparatus, a cross brace extending between said front and rear braces and comprising a support for one side of the Reeves drive within the apparatus, the opposite side of said Reeves drive being supported in an end housing, openings in said front brace for access to the interior of said apparatus and covers for said openings, said covers when in place upon said brace presenting a substantially flush appearance with the front of the apparatus.

2. An apparatus for cutting successive sheets from a continuous web, said apparatus comprising a pair of rotating cutting knives and means for adjusting the speed of rotation thereof, said cutting knives being mounted between end housings of said apparatus and said adjusting means including a Reeves drive, a power connection from a power source to said Reeves drive and a power connection from the Reeves drive to said cutting knives, said power connection being housed in an end housing, a front brace between said end housings, said brace substantially enclosing the front of the apparatus, a rear brace between said end housings, said rear brace substantially enclosing the rear of the apparatus, a cross brace extending between said front and rear braces and comprising a support for one side of the Reeves drive within the apparatus, the opposite side of said Reeves drive being supported in an end housing, openings in said front brace for access to the interior of said apparatus and covers for said openings, said covers when in place upon said brace presenting a substantially flush appearance with the front of the apparatus.

ALBERT F. SHIELDS.
